SMOKING PIPE

Henry Clarence McClune, Topeka, Kans.

Application September 3, 1936, Serial No. 99,292

2 Claims. (Cl. 131—12)

This invention appertains to new and useful improvements in smokers' appliances and more particularly to a smoking pipe.

The principal object of the present invention is to provide a pipe structure in which all moisture is collected and absorbed while the smoke is by-passed in a manner so that it will not receive any of the moisture, to the end that the smoke drawn in by the smoker will be dry.

Other important objects and advantages of the invention will become apparent to the reader of the following specification.

In the drawing:—

Figure 1 represents a longitudinal sectional view through the pipe.

Figure 2 is a cross section on the line line 2—2 of Figure 1.

Figure 3 is a side elevational view of the absorber.

Figure 4 is a longitudinal sectional view through the absorber.

Referring to the drawing wherein like numerals designate like parts, it can be seen that numeral 5 denotes the bowl of the pipe while numeral 6 is the shank which extends therefrom. In this shank 6 is the pocket 7 into which extends the duct 8 from the bowl 5.

Numeral 9 is the mouthpiece which is provided with the reduced extension 10 adapted to be wedged into the outer end of the pocket 7.

Extending around the pocket 7 is the arcuate-shaped by-pass duct 11 communicating at one end with the duct 8 and at its rear end with the rear end of the pocket 7 so that when the reduced extension 10 of the mouthpiece 9 is inserted, the branch duct 12 therein will register with the outer end of the arcuate duct 11. The duct 13 through the mouthpiece is aligned with the pocket 7.

Within the reduced extension 10 of the mouthpiece 9 is a branch duct A extending from branch duct 12 so that when mouthpiece 9 and reduced extension 10 are inserted so that reduced extension 10 is wedged into the outer end of pocket 7 the lower end of branch duct A touches absorber 9 so that moisture collecting in branch

duct 12 and duct 13 is drained into and absorbed by absorber 9.

A plug 11a is provided in the upper portion of the shank 6 so as to permit access to the duct 11 so that the same can be readily cleaned when desired. 5

In the pocket 7 is the absorber 17 which consists of a frame made up of the two annular end members 15—16 connected by the member 17 and as is shown in Figure 4, a hook-shaped member 18 is provided on the annular member 16. A body 19 of absorbing material is disposed in the frame with its end portions disposed into the annular members 15—16. 10

The hook member 18 engages over the cleat 20 15 in the forward end portion of the pocket 7 so as to prevent shifting of the absorbent device.

It can be seen, that in use, moisture is collected by the absorber, while dry smoke passes through the duct 11 to the smoker's mouth. 20

While the foregoing specification sets forth the invention in specific terms, it is to be understood that numerous changes in shape, size and materials may be resorted to without departing from the spirit and scope of the invention as claimed 25 hereinafter.

Having described the invention, what is claimed as new is:—

1. In a pipe structure, a stem having a pocket therein, a moisture absorbing unit in the pocket, 30 said unit including a frame, absorbing material in the frame, a formation in the pocket adjacent one end thereof, and a hook member on the frame engaged with the said formation to prevent displacement of the unit from the pocket. 35

2. In a pipe structure, a stem, a pocket in the stem, an absorbent unit in the pocket for absorbing moisture, and a plug for wedging disposition in the outer end of the pocket and having a mouth piece attachable nipple extending therefrom, said plug being provided with a projecting teat through which a duct inclines, said duct terminating in an opening adjacent the bottom of the said pocket. 40
